ROLLER-TYPE FLUID PUMP

Ernest E. Cook, Anoka, Minn., assignor to Hypro Engineering, Inc., Minneapolis, Minn., a corporation of Minnesota

Filed May 21, 1962, Ser. No. 70,221

Term of patent 14 years

(Cl. D65—1)

FIGURE 1 is a front perspective view showing my new design for a roller-type fluid pump;
FIGURE 2 is a top plan view thereof;
FIGURE 3 is a front elevational view;
FIGURE 4 is a side elevational view; and
FIGURE 5 is a rear elevational view.
The side opposite that shown in FIG. 4 is a mirror image thereof.

I claim:

The ornamental design for a roller-type fluid pump, substantially as shown and described.
